UNITED STATES PATENT OFFICE.

STEPHEN J. AUSTIN, OF TERRE HAUTE, INDIANA.

BEARING FOR PLATFORM-SCALES.

SPECIFICATION forming part of Letters Patent No. 516,958, dated March 20, 1894.

Application filed August 16, 1893. Serial No. 483,249. (No model.)

To all whom it may concern:

Be it known that I, STEPHEN J. AUSTIN, of Terre Haute, in the county of Vigo and State of Indiana, have invented a certain new and useful Improvement in Scales, of which the following is a full, clear, and exact description, reference being had to the accompanying drawings, forming part of this specification.

10 My invention relates to an improvement intended more particularly for track and wagon scales; and my invention consists in features of novelty hereinafter fully described and pointed out in the claims.

15 Figure I is a detail, vertical section, taken on line I—I, Fig. III, and illustrative of my invention. Fig. II is a detail elevation. Fig. III is a vertical, transverse section, taken on line III—III, Fig. II.

20 Referring to the drawings, 1 represents part of the foundation of the scale, having the usual standards 2, upon which the ends of the levers 3 rest with a knife edge bearing 4; only one of the levers, or a lever for one side of the 25 scale only is shown in the drawings, as this is sufficient to illustrate my invention, which does not, in itself, relate to the levers.

5 represents part of the platform of the scales, which has bearing plates 6 over the 30 levers 3. 7 is a bridge-piece having knife edge bearing 8 on the lever 3, there being, of course, a bridge-piece for each lever.

My present invention relates to the manner of mounting the platform on the bridge piece 7.

35 9 represents pear shaped rockers located between the bearing plate 6 and the ends of the bridge-piece; these rockers having convex, upper ends 10, fitting in concave recesses 11 in the bearing plate; the radius of the recess 11 being greater than the radius of the upper end of the rockers, so as to permit of a universal joint between the rockers and the bearing plate. The lower ends of the rock-

ers have convex bearing surfaces 12, resting upon convex bearing surfaces 13 on the bridge-piece, the bridge-piece being preferably recessed, as shown at 14, and the bearing surfaces 13 being at the bottom of these recesses. These surfaces 12 and 13 form reversed spherical bearings, which are very sensitive in their 50 action, as well as being universal.

For the purpose of keeping the bearing surfaces from slipping, one upon the other, I fix pins 15 in the bridge, the upper ends of which are received by sockets 16 formed in the lower 55 ends of the rockers, the sockets enlarging inwardly so as not to interfere with the universal movement of the bearing. This manner of supporting the platform provides a universal, or so to speak, ball and socket bearing 60 at both ends of the rockers, thus relieving the knife edges and other parts from any wear or side strain which would interfere with the accurate working of the scale, and at the same time holding the platform in position by natural gravity, the rockers being eccentric or self-righting when resting on a flat or convex surface.

I claim as my invention—

1. In a scale, a self righting rocker of pear 70 shape formed with a convex upper end, and with a convex lower end of greater diameter than the convex upper end; substantially as described.

2. In a scale, the combination of a lever, a 75 bridge-piece, a platform, and rockers located between the platform and bridge-piece; said rockers having convex, lower ends bearing against or fitting in recesses in the bridge-piece and bearing against convex surfaces on 80 the bridge-piece, and pins 15; substantially as and for the purpose set forth.

STEPHEN J. AUSTIN.

In presence of—

ELMER F. WILLIAMS,
RICHARD V. NEWTON.
